UNITED STATES PATENT OFFICE.

MILLS COLLINS FOSTER, OF REGINA, SASKATCHEWAN, CANADA.

TRAIN-STOPPING DEVICE.

1,407,742.

Specification of Letters Patent. Patented Feb. 28, 1922.

Application filed October 29, 1921. Serial No. 511,360.

To all whom it may concern:

Be it known that I, MILLS COLLINS FOSTER, a subject of the King of Great Britain, and resident of the city of Regina, in the Province of Saskatchewan and Dominion of Canada, have invented certain new and useful Improvements in Train-Stopping Devices, of which the following is a specification.

This invention relates to improvements in train stopping devices, and the objects of the invention are to provide an effective, simple and economical device of this kind for bringing trains and the like automatically and quickly to a standstill when rendered necessary through unforeseen circumstances.

The invention consists essentially in the combination with a tripping device on the railway track of means carried by the locomotive adapted to be operated by said tripping device whereby the air brakes are instantaneously and automatically applied or the train otherwise brought to a standstill.

With the foregoing and other objects in view, reference is now had to the drawings in which like characters of reference indicate corresponding parts in each figure, and in which:

Figure 1 is a side view of the trip mechanism of my device applied to a railway track.

Figure 2 is a similar view, showing the trip lever or arm in operation.

Figure 3 is a top view partly sectional of Figure 1.

Figure 4 is an end view of Figure 1.

Figure 5 is an end view of Figure 2.

Figure 6 is a sectional side view of the knife mechanism showing the air tube there-through.

Figure 7 is a front elevation of Figure 6.

Figure 8 is an end view of Figure 7.

Figures 9 and 10 show front and side views respectively of the appliance attached to a locomotive.

Referring to the drawings:

10 is a suitable frame adapted to rest on the railroad ties 11 between the fish-plate 12 and the rails 13 and provided with a suitable support 14 at one end thereof and downwardly bent at the other end. 15 is a rocker-shaft or arm in the vertically bent end of the frame 10 having mounted thereon the trip arm 17 and the link 18 connected at its other

end to the knife operating arm 19 on the frame 10 and slidably secured thereto by means of the bracket 20.

Referring to the knife mechanism carried on the locomotive or other rolling stock, 21 is a plate slidably mounted between the guideways 22 and formed with an aperture 23 therein adapted to receive therethrough the air-brake tube 24 and provided below and adjacent to said aperture with a knife or cutter 25. 26 is a suitable roller secured on the lower end of the plate 21 adapted to contact with the knife-operating arm 19 in an inoperative position as hereinafter more fully described.

The plate guideways 22 are bolted or otherwise suitably attached to the locomotive by plates provided with bolt apertures 27 therein, and the roller 26 is held in place by the brackets 28. The air tube 24 passes through the aperture 23 in the plate 21 and is coupled at one end to a pipe 29, in turn connected to a T on the train line leading to the front of the locomotive. The other end of the tube 24 is provided with a dummy coupler suspendedly secured through a chain 31 to the locomotive and in such manner as to clear the tube 24 from the knife-edge 25.

32 is a shut-off valve on the pipe 29 for closing same while the member 24 is being replaced after the operation of stopping a train, and 33 is the flange of a railway wheel 34 adapted to turn on the track 13.

From the foregoing the operation of my device will be more or less apparent. The movable trip mechanism 10 having been placed in position on the track (as shown in Figure 1), the moving flanged wheel of the locomotive will contact with the trip arm 17, forcing it downwardly and causing the knife-operating arm 19 to move upwardly (as shown in Figure 2), thereby moving upwardly through the roller 26 the plate 21 carrying the knife or puncturing means 25 to penetrate the flexible air tube member 24 to release the air therein, and thus cause the air-brakes to be applied automatically to bring the train to a standstill.

As many changes could be made in the above construction and many apparently widely different embodiments of my invention within the scope of the claims, constructed without departing from the spirit or scope thereof, it is intended that all mat-

ter contained in the accompanying specification and drawings shall be interpreted as illustrative and not in a limiting sense.

It may be mentioned that my invention is particularly adaptable for use at interlocking diamonds at grades where it is intended to supersede the derailing joint now in general use, being operated by the tower man in the same way as the derailing joint, but, instead of stopping the trains by derailment, it stops them as already mentioned, by setting the air brakes.

What I claim as my invention is:

1. A train stopping device comprising in combination with a track and a locomotive thereon, a frame adapted to fit between the fish-plate and the rail, a rocker-shaft therein, a trip arm on said rocker-shaft, a link mounted on said shaft and connecting with a knife-operating arm slidably secured on the frame, a knife-plate slidably mounted on the locomotive, a roller on the lower end thereof adapted to contact with the knife-operating arm, an aperture in said plate, a flexible air tube member adapted to pass therethrough coupled at one end to pipe connecting means with the air-brake system of the train and provided at the other end with a dummy coupler loosely suspended and supported from the locomotive, and means for closing said pipe connecting means.

2. In a device of the class described in combination with a railroad track and a train thereon, trip mechanism on the track comprising an operating arm and a trip member adapted in combination with the train wheel to force said operating arm up-

wardly, an apertured and slidably mounted plate carried by the train adapted to contact with said operating arm, cutting means on said plate and a flexible air tube connected with the train air-brake system passing through said plate adjacent to said cutting means, whereby on the operating arm being raised, the cutting means will penetrate said flexible air tube.

3. In a device of the class described in combination, tripping means on the railroad track adapted in operation to raise an operating arm, a slidably mounted and apertured member on the train adapted to contact with said operating arm, cutting means carried by said train member and flexible tube connection with the train brake system passing therethrough and provided with a dummy coupler and adapted in an operative position to contact with said cutting means.

4. In a device of the class described in claim 1, trip mechanism on the railroad track adapted to control an operating arm, puncturing mechanism carried by the train adapted to be operated by said operating arm and air conveying means connected with the train air-brake system passing through said puncturing mechanism whereby on the trip mechanism being operated by the train wheels, the brakes are automatically applied and the train stopped.

In witness whereof I have hereunto set my hand in the presence of two witnesses.

MILLS COLLINS FOSTER.

Witnesses:

JOHN K. FRUM,

EDWARD WALTER SALMON.
